LAMP SOCKET FOR TUBULAR FLUORESCENT LAMPS

Herman L. Goebel, Chicago, Ill., assignor to International Molded Plastics, Inc., Cleveland, Ohio, a corporation of Ohio

Application March 8, 1946, Serial No. 652,986

2 Claims. (Cl. 173—328)

1

The invention relates to improvements in lamp sockets and more particularly to the novel socket construction for electric lamps of the double ended discharge type, which are more commonly known as fluorescent lamps, in which a filamentary electrode is mounted at each end of the lamp.

An object of the present invention is to provide a socket construction of the type referred to wherein the lamp may be inserted readily into and positioned in the socket and positively locked therein to prevent unwarranted displacement thereof.

Another object of the invention is to provide a lamp socket housing having means therein to positively engage terminal prongs on a lamp when the lamp is rotatable relative to said housing in either direction for a predetermined distance into abutment with positive stops formed in said socket.

Another object of the invention is to provide a lamp socket of moldable material with integral means to bind a plurality of spring contacts therein firmly.

Another object is to provide a one-piece lamp socket body having spring contact tensioning means therein effective to urge a plurality of contacts into electrical contact with terminal prongs projected through openings in said body.

Another object is to provide a lamp socket with a slotted receiving opening having a relatively wide entrance to facilitate the insertion of a plurality of terminal prongs carried on a lamp mounted therein.

Another object is to provide a socket for electric lamps which is not expensive to manufacture and which is rugged in construction, easy to assemble and highly efficient in use.

Other and further objects of the present invention will be apparent from the following description and claims and are illustrated in the accompanying drawing which, by way of illustration, shows a preferred embodiment and the principle thereof and which is considered to be the best mode contemplated for applying that principle. Other embodiments of the invention embodying the same or equivalent principle may be used and structural changes may be made as desired by those skilled in the art without departing from the present invention and a purview of the appended claims.

In the drawing:

Fig. 1 is an assembly view of a fluorescent lamp and mounting sockets embodying features of the invention.

2

Fig. 2 is an elevational view of one of the sockets.

Fig. 3 is an end view of said socket.

Fig. 4 is an elevational view of the socket, on an enlarged scale, looking at the rear side thereof with the backing plate removed.

Fig. 5 is a longitudinal sectional view taken substantially on line 5—5 of Fig. 4.

Fig. 6 is an enlarged transverse sectional detail view taken on line 6—6 of Fig. 2.

In the drawing, an electrical discharge device, such as a fluorescent lamp 11 of well known construction, is shown with its ends mounted in a pair of identical sockets 12 embodying the features of the present invention. The lamp 11 consists of a tube of transparent material having end plates 13 hermetically sealed to the ends thereof, and a pair of terminal contact prongs 14 projecting outwardly from each end plate 13.

The terminal prongs 14 constitute means for conducting electricity to the filamentary electrode (not shown) contained within the lamp and afford means for securely mounting said lamp in the sockets 12 in such manner that the lamp may be easily inserted or removed therefrom while at the same time be securely held against unintended displacement.

The sockets 12 are mounted in spaced relation upon a suitable support 15, or the like, as by means of screws 16 which extend through the base portion 17 of each socket and receive nuts 18 on the projecting ends thereof. Inasmuch as the sockets are identical in their construction, the description will concern itself with the specific structure of one of these sockets.

As best shown in Fig. 2, the socket 12 includes the base portion 17 and a body portion 19 which extends upwardly therefrom and is of smaller cross-sectional area than the area of the base 17. The socket preferably is fashioned in one piece from moldable material such as "Bakelite," or the like, and the body portion 19 includes a front wall 21 having side walls 22 and an end wall 23 extending rearwardly from the front wall to provide a relatively shallow housing structure. The side walls 22 are integrally joined with rearwardly extending top and side walls 24 on the base 17, and a centrally located longitudinal rib 25 is fashioned on the back face of the front wall 21, which rib is substantially coextensive with the combined length of the body 19 and base 17.

A pair of diametrically opposed arcuate slots 26 are provided in the front wall 21 of the body portion 19 inwardly of the upper end thereof, said

slots bridging the longitudinal rib 25. A straight slot 27, also provided in the front wall 21 of the body and extending into the rib 25, intersects both arcuate slots 26 midway between their ends and opens into the upper end of the body 19. As best illustrated in Figs. 2 and 3, the open end of the straight slot 27 is flared, as at 28, for a purpose to be described hereinafter. It should be noted at this time that the respective ends of the arcuate slots 26 are spaced apart to provide transverse bridge portions 31 connecting the semicircular ribbed wall portions 32, within the confines of said slots, with the front wall 21 of the body.

The base portion 17 of the lamp socket is provided on its inside faces with two pairs of shoulders 33 which are adapted to have rested firmly thereagainst leg portions 34 extending substantially at right angles from one end of a pair of spring contact elements 35 arranged within the hollow portion of the body 19. These leg portions afford means for electrically connecting the socket with a current source or with an auxiliary fixture of conventional construction (not shown). Upon referring to Fig. 4, it will be observed that the spring contact elements 35 extend upwardly, one on either side of the rib 25, and are suitably formed adjacent their upper ends with arcuately shaped portions 36 and outwardly flared ends 37. The arcuately shaped portions are disposed substantially to the rear of the end areas of the arcuate slots 26, and normally said portions rest against shoulders 38, one formed on the back face of each transverse bridge portion 31.

When a lamp is to be mounted in the sockets 12, the terminal contact prongs 14 thereof are held in alignment with and are moved downwardly into the straight slot 27. Such movement of the prongs 14 into said slot is greatly facilitated by the flared end 28 thereof. When the leading prong 14 comes into contact with the lower wall of the lowermost arcuate slot 26, the trailing prong 14 is in alignment with the upper arcuate slot 26. The lamp then is rotated in either direction to position the prongs 14 at diametrically opposed ends of the slots 26. When the prongs are carried into this position they are brought into contact with the spring contact elements 35 which are urged outwardly transversely a distance sufficient to enable the prongs to pass onto the end areas of the arcuate portions 36 thereof, whereupon the inherent resiliency of the spring contacts urges them inwardly to position portions thereof in the path of the prongs 14 so as to prevent unintended movement of the prongs away from the ends of the slots 26. Such retention of the prongs is greatly facilitated by providing slight enlargements or protuberances 39 at the ends of the arcuate portions 36 of the spring contacts.

The tension of the spring contacts 35 is materially increased due to the formation of a pair of lugs 41 on the inside face of the front wall 21. These lugs have their inwardly disposed ends in substantial alignment with the normal position of the spring contacts 35 when the latter are relieved of tension upon the removal of prongs 14. However, when the lamp is in place with the

prongs 14 contacting the spring contacts 35 so as to hold them tensioned outwardly, said spring contacts are bowed at their point of contact with the lugs 41. The lugs 41 also afford means to frictionally retain the spring contacts 35 in place within the body of the lamp socket prior to their being firmly secured upon assembly of the lighting fixture.

The present construction of the lamp socket is such that the lamp 11 is positively secured in a position of use by the tension of the spring terminal contacts 35, and said locking engagement may be overcome easily upon rotating the lamp in a direction to align the two prongs 14 with the straight slot 27. The presence of the bridge portions 31 at the effective ends of the arcuate slots 26 prevents excessive rotation of the lamp into such positions as might result in an incomplete or defective circuit being maintained between the prongs and spring terminal contacts. These positive stops for the prongs also serve to assure the operator that the lamp has been rotated sufficiently to insure contact and to prevent its displacement.

Although an exemplary form of socket construction has been shown in the drawing and described in detail in the foregoing specification, it should be understood that the socket may embody a variety of modifications in detail construction without departing from the spirit of the invention or the scope of the appended claims.

I claim:

1. A socket for electric lamps comprising a body of insulating material, said body being provided in a face thereof with a straight slot opening into one end of said body, and two pairs of opposed arcuate slots with each pair spaced by a bridge and connecting with said straight slot, said bridges being disposed at right angles to said straight slot, and spring terminal contacts mounted in said body adjacent said arcuate slots, one on each side of said straight slot.

2. In a socket for electrical lamps having a pair of spaced contact pins at each end thereof, a body of insulating material having in one face thereof a straight slot opening into one end of said body, and two pairs of opposed arcuate slots with each pair spaced by a bridge and connecting with said straight slot, said bridges being disposed at right angles to said slot.
